CUTTING TOOL

Lawson A. Smith, Los Angeles, Calif., assignor to
Robert H. Clark, Los Angeles, Calif.

Application February 18, 1944, Serial No. 522,901

6 Claims. (Cl. 77—58)

1

This invention has to do with a cutting tool and has particular reference to that type of tool used in performing the operation commonly known as spot facing or counterboring.

In the manufacture of various machine parts or devices it is frequently desired to finish or machine a surface in the immediate vicinity of or around a hole or bore. Devices known as counterbores or spot facers are used for this purpose, it being common to provide such devices with pilots that enter the hole and with blades which act to cut the surface desired. A common difficulty encountered with such tools is that a burr is formed at the point of joinder of the surface and hole with the result that the tool becomes stuck or fails to operate smoothly. With most tools of the general character referred to it is not at all uncommon for the pilots to become stuck causing considerable inconvenience and often damage.

It is an object of this invention to provide a tool that will effectively spot face or counterbore and which performs such operations without the formation of a burr such as to cause sticking of the pilot or improper operation of the tool generally.

It is another object of my invention to provide a tool of the character mentioned embodying an improved arrangement and formation of cutter blades. By my invention I provide cutter blades which are carried by the body of the tool so that they can be adjusted to cut surfaces of various sizes and the cutting edges of the blades are disposed to have a most desirable cutting action.

Another object of the invention is to provide a tool of the character referred to in which the pilot is removable making it possible to provide the tool with pilots of various sizes in order to fit various holes.

Another object of the invention is to provide a tool of the character mentioned in which the pilot is formed of a head detachable from a stem so that a common stem can be employed and various heads can be used on the stem to accommodate holes of various sizes.

The various objects and features of my invention will be fully understood from the following detailed description of a typical preferred form and application of the invention, throughout which description reference is made to the accompanying drawing, in which:

Fig. 1 is a side elevation of a tool embodying the present invention, being a view taken in a direction to show the forward or leading side of one of the blades of the tool. Fig. 2 is a view similar to Fig. 1 taken with the tool rotated through 90°. Fig. 3 is a bottom end view of the tool of the present invention being a view taken as indicated by line 3—3 on Fig. 1.

Referring to the drawing, the tool of the pres-

2

ent invention embodies, generally, a body 10, a shank 11 on the body for mounting it in a machine of suitable character, blades 12 carried by the body to project from the lower end thereof, means 13 operable to clamp the blades in the desired position on the body, a pilot 14 carried by the body to project from the lower end thereof and to cooperate with the blades 12, and means 15 for retaining the pilot on the body.

10 The body 10 is preferably an elongate element proportioned to firmly carry the blades 12, to carry the means 13 and to carry the pilot 14. In the preferred form of the invention the body is hexagonal in cross-sectional configuration, as is shown throughout the drawing.

The shank 11 is preferably formed integral with the body 10 to project from the upper end thereof and is proportioned, shaped and finished to be accommodated in a suitable machine. In 20 accordance with common machine shop practice I have shown a tapered shank, round in cross section and provided with a flattened part 16 at its upper end.

The invention provides one or more blades 12 to be carried by the body 10 to project from the lower end thereof, the lower end portion of each blade being dressed or sharpened to have the desired cutting action. In the preferred form of the invention the lower end 17 of the body 10 is 30 flat or lie in a plane transverse of the longitudinal axis of the tool, and the cutters are carried by the body to project from the lower end of the body.

It is preferred, in practice, to provide the tool 35 with two blades 12 and to locate them diametrically opposite each other or in opposite sides of the body 10 in the general arrangement shown throughout the drawing. The body 10 has channels 18 cut in diametrically opposite sides to carry the blades 12, the channels being made sufficiently wide to slidably pass the blades and being made sufficiently deep so that the blades are well seated in the body to be firmly supported therein. By making the channels fairly deep 45 the bottoms 19 of the channels are considerably wider or of greater area than they would be if the channels were shallow, this being due to the fact that the body is hexagonal in cross section and the surfaces 19 become wider as the channels are made deeper.

In accordance with the preferred form of my 50 invention I pitch or incline the channels 18 so the blades are carried to extend downwardly and outwardly from the lower end 17 of the body. It is to be understood that the channels are pitched to correspond to each other so that the blades are carried at corresponding angles and that the angles are such that the channels extend a considerable distance upwardly in the body from the lower end to give the blades ample support.

The lower end portion of each blade is dressed

or finished to have a cutting edge 20 designed to act on the material against which the tool is fed. In the drawing I have shown the ends of the blades shaped and dressed for spot facing operations and, therefore, they are disposed at right angles to the longitudinal axis of the tool. It is to be understood that if a special configuration is desired the edges 20 or the ends of the blades can be dressed accordingly. It is to be noted from the drawing that the blades are dressed so that the cutting edges 20 are at their forward or outer parts so that as forces are applied in the course of operation they are transmitted through the blades onto the bottoms 19 of the channels 18. Suitable clearance may be provided behind the edges 20 at the bottom of the cutters. It is also to be noted from Fig. 3 of the drawing that the arrangement which I have provided causes the edges 20 to be disposed tangent to a circle concentric with the axis of the tool rather than being radial relative to the axis of the tool. By thus locating the edges 20 I obtain a desirable cutting angle. It is to be understood, of course, that the front face 21^x of each blade can be dressed or shaped so that the edge 20 has the proper angle relative to the work and so that there is proper chip clearance as work progresses. In the case of a blade dressed for spot facing it is also desirable that the outer tip 21 be finished so that it is substantially perpendicular as shown in the drawing.

The means 13 provided for holding the blades in place in the channels 18 of the body may be any suitable means that will serve this function. In the preferred construction I employ a clamp plate 25 to engage the outer sides of each blade 12 and I employ a cap screw 26 to extend through the plate to thread onto the body adjacent the channel which carries the blade. The plate 25 is preferably a washer-like element. In the form of construction illustrated in the drawing the channels 18 are rather deep in the sides of the body and, therefore, the body is countersunk at 27 to accommodate the plates 25, the countersinks being made deep enough so that the plates 25 have bearing engagement on the outer surfaces of the blades 12. By using ordinary cap screws 26 as the means for clamping the plates 25 against the cutters the tool can be adjusted by the use of an ordinary wrench thus making it simple and convenient to handle.

The pilot 14 includes a head 30 projecting below the lower end 17 of the body 10 from a point above the edges 20 of the blades to a point a considerable distance beyond the blades. The head 30 is made long enough to give an effective bearing in the hole in which the tool is operated. In practice the head is turned and finished to work in the hole or bore with sliding clearance and thus operates as a pilot or steadyng device for the entire tool.

A feature of the present invention is the provision of recesses 31 in opposite sides of the head 30 of the pilot 14 to receive the lower or projecting end portions of the blades 12, so that the cutting edges 20 of the blades overlap or extend inwardly into the recesses. The head 30 is turned uniformly from one end to the other or from a point above the edges 20 to the lower end of the head so that during operation of the tool the head occupies the upper end portion of the hole in which the tool is operated and acts to iron out or remove any burr that might tend to form at the junction of the hole and the plane of cut of the edges 20. The relationship of the cutting

edges 20, the head 30 and the notches 31 in the head will be apparent from an examination of the drawing.

The head 30 of the pilot may be secured to the lower end of the body 10 in any suitable manner. In the preferred construction a stem 35 is provided for this purpose and the head 30 is made detachable from the stem. In the construction shown the head 30 has a central bore 36 which receives the lower end portion of the stem and a suitable set screw 37 is provided for locking the head on the stem. The stem projects upwardly from the head 30 to slidably fit into a socket 38 formed centrally in the body 10 from the lower end 17. A set screw 39 is carried by the body to be operated into engagement with the stem 38 to hold it in the body. With the construction just described the pilot can be completely detached from the body at will and heads of various sizes can be installed on the stem as desired. It is to be understood, of course, that each head employed is notched at 31 so that the cutting edges 20 overlap the outer or finished face of the head so the tool operates without establishing an undesirable burr.

Having described only a typical preferred form and application of my invention I do not wish to be limited or restricted to the specific details herein set forth, but wish to reserve to myself any variations or modifications that may appear to those skilled in the art and fall within the scope of the following claims.

Having described my invention, I claim:

1. In a rotary cutting tool, an elongate central body having a shank at one end and having an angularly disposed channel in one side with a bottom in a plane tangent and parallel to the body and pitched to extend lengthwise and sideways of the body to open at the other end of the body, a flat elongate cutter in the channel with its inner side seated radially inward against the bottom of the channel and having an outer end portion projecting from said other end of the body, which end portion has a cutting edge extending sideways of the body and substantially normally to the longitudinal axis of the body, means retaining the cutter in the channel, the body having a central socket entering it from its said other end, a pin supported in the socket with an outer portion projecting beyond said other end of the body, a set screw retaining the pin in the socket, a pilot head carried on the outer portion of the pin, and a set screw carried by the head engaging the pin to retain the head thereon, the head having a lower portion spaced below the cutting edge and round in cross section with the plane of its outer surface intersecting the path of the cutting edge and also having an upper portion of reduced width to accommodate the cutter and projecting upward from the lower portion and bearing against the said other end of the body to be spaced from the cutting edge and having curved sides in the plane of the outer surface of the lower portion.

2. In a rotary cutting tool, an elongate central body having a shank at one end and having two diametrically opposite side channels in the body, the channels being angularly disposed and pitched in opposite directions and having bottoms in parallel planes tangent and parallel to the body and each pitched to extend lengthwise and sideways of the body to open at the other end of the body, a flat elongate cutter in each channel with its inner side seated radially inward against the bot-

tom of the channel and having an outer end portion projecting from said other end of the body, which end portion has a cutting edge extending sidewise of the body and substantially normal to the longitudinal axis of the body, means retaining the cutters in the channels, the body having a central socket entering it from its said other end, a pin held in the socket, and a pilot head carried by the pin having a lower portion spaced below the cutting edge and round in cross section with the plane of its outer surface intersecting the path of the cutting edge and also having an upper portion of reduced width to accommodate the cutters and projecting upward from the lower portion and bearing against the said other end of the body to be spaced from the cutting edge and having curved sides in the plane of the outer surface of the lower portion.

3. In a rotary cutting tool, an elongate central body having a shank at one end and having two diametrically opposite side channels in the body, the channels being angularly disposed and pitched in opposite directions and having bottoms in parallel planes tangent and parallel to the body and each pitched to extend lengthwise and sidewise of the body to open at the other end of the body, a flat elongate cutter in each channel with its inner side seated radially inward against the bottom of the channel and having an outer end portion projecting from said other end of the body, which end portion has a cutting edge extending sidewise of the body and substantially normal to the longitudinal axis of the body, means retaining the cutters in the channels, the body having a central socket entering it from its said other end, a pin held in the socket, and a pilot head carried by the pin having a lower portion spaced below the cutting edge and round in cross section with the plane of its outer surface intersecting the path of the cutting edge and also having an upper portion of reduced width to accommodate the cutters and projecting upward from the lower portion and bearing against the said other end of the body to be spaced from the cutting edge and having curved sides in the plane of the outer surface of the lower portion, the bottoms of the channels being tangent to the socket in the body.

4. In a rotary cutting tool, an elongate central body having a shank at one end and having an angularly disposed channel in one side with a bottom in a plane tangent and parallel to the body and pitched to extend lengthwise and sidewise of the body to open at the other end of the body, a flat elongate cutter in the channel with its inner side seated radially inward against the bottom of the channel and having an outer end portion projecting from said other end of the body, which end portion has a cutting edge extending sidewise of the body and substantially normal to the longitudinal axis of the body, means retaining the cutter in the channel including a clamp member engaged in a transverse opening removed from the channel toward the first mentioned end of the body, the body having a central socket entering it from its said other end, a pin supported in the socket with an outer portion projecting beyond said other end of the body, a set screw retaining the pin in the socket, a pilot head carried on the outer portion of the pin, and a set screw carried by the head engaging the pin to retain the head thereon, the head having a lower portion spaced below the cutting edge and round in cross section with the plane of its outer surface intersecting the path of the cutting edge and also having an upper por-

tion of reduced width to accommodate the cutter and projecting upward from the lower portion and bearing against the said other end of the body to be spaced from the cutting edge and having curved sides in the plane of the outer surface of the lower portion.

5. In a rotary cutting tool, an elongate central body having a shank at one end and having two diametrically opposite side channels in the body, the channels being angularly disposed and pitched in opposite directions and having bottoms in parallel planes tangent and parallel to the body and each pitched to extend lengthwise and sidewise of the body to open at the other end of the body, a flat elongate cutter in each channel with its inner side seated radially inward against the bottom of the channel and having an outer end portion projecting from said other end of the body, which end portion has a cutting edge extending sidewise of the body and substantially normal to the longitudinal axis of the body, means retaining the cutters in the channels including separate clamp members engaging the cutters and carried in diametrically disposed transverse openings in the body between the channels and the first mentioned end of the body, the body having a central socket entering it from its said other end, a pin held in the socket, and a pilot head carried by the pin having a lower portion spaced below the cutting edge and round in cross section with the plane of its outer surface intersecting the path of the cutting edge and also having an upper portion of reduced width to accommodate the cutters and projecting upward from the lower portion and bearing against the said other end of the body to be spaced from the cutting edge and having curved sides in the plane of the outer surface of the lower portion.

6. In a rotary cutting tool, an elongate central body having a shank at one end and having two diametrically opposite side channels in the body, the channels being angularly disposed and pitched in opposite directions and having bottoms in parallel planes tangent and parallel to the body and each pitched to extend lengthwise and sidewise of the body to open at the other end of the body, a flat elongate cutter in each channel with its inner side seated radially inward against the bottom of the channel and having an outer end portion projecting from said other end of the body, which end portion has a cutting edge extending sidewise of the body and substantially normal to the longitudinal axis of the body, means retaining the cutters in the channels including separate clamp members engaging the cutters and carried in diametrically disposed transverse openings in the body between the channels and the first mentioned end of the body, the body having a central socket entering it from its said other end, a pin held in the socket, and a pilot head carried by the pin having a lower portion spaced below the cutting edge and round in cross section with the plane of its outer surface intersecting the path of the cutting edge and also having an upper portion of reduced width to accommodate the cutters and projecting upward from the lower portion and bearing against the said other end of the body to be spaced from the cutting edge and having curved sides in the plane of the outer surface of the lower portion, the bottoms of the channels being tangent to the socket in the body.
